UNITED STATES PATENT OFFICE.

EDMUND M. REDDY, OF OSSINING, NEW YORK.

CEILING OUTLET-BOX.

1,032,504.

Specification of Letters Patent. Patented July 16, 1912.

Application filed February 9, 1912. Serial No. 676,629.

To all whom it may concern:

Be it known that I, EDMUND M. REDDY, a citizen of the United States, and residing at Ossining, in the county of Westchester and State of New York, have invented certain new and useful Improvements in Ceiling Outlet-Boxes, of which the following is a specification, such as will enable those skilled in the art to which it appertains to make and use the same.

This invention relates to what are known as, outlet boxes, used in wiring a fire-proof or other building for electric lighting and other purposes, and the object thereof is to provide an improved device of this class designed for use as a ceiling outlet box, and in connection with chandeliers and other hanging apparatus, and with this and other objects in view the invention consists in a device of the class specified, constructed as hereinafter described and claimed.

The invention is fully disclosed in the following specification of which the accompanying drawing forms a part in which the separate parts of my improvement are designated by suitable reference characters in each of the views, and in which:—

Figure 1 is a cross sectional view of a floor and ceiling construction showing the method of using my improvement;—Fig. 2 a top plan view of my improved outlet box, and Fig. 3 a bottom plan view thereof.

In the drawing forming part of this specification I have shown a floor and ceiling construction involving ordinary I-beams *a* together with the usual concrete *b*, and the flooring *c* laid on ashes or similar material *c*² placed on the concrete. In forming the concrete part of the floor and ceiling construction a wood frame or support is provided consisting of, boards *d*—*d*² and *d*³ placed as shown so as to provide a sort of mold into which the concrete is poured, and this part of the drawing is intended to illustrate the method of using my improved ceiling outlet box *e*.

The outlet box *e* is rectangular in horizontal section, in the form of construction shown, but may be of any desired shape, and is open at the top when in use, and provided with a bottom *e*² having a central depending rim *e*³ of less transverse dimensions than the body of the box, and preferably about one fourth the depth of said body of the box. The bottom *e*² of the box is provided with spaced holes *f* which are nor-

mally closed by plates *f*² in the usual manner but which, when the box is put in use, are broken out so as to leave the holes *f* or a part thereof free for the passage of the lead pipes *g*, which are used in the usual manner, and the end portions *g*² of which are bent downwardly through the box and passed through the openings *f* two of said pipes being thus shown in the drawing. The center of the bottom of the box is also provided with a central opening or hole *h* similar to the holes *f*, but which is intended to serve as an attachment, or means of attaching a threaded plug *h*², which plug serves as a support or attachment for an electric, or any other illuminating hanger, lighting device, or other article. The plug *h*² may be passed downwardly through the bottom of the box as shown, and may be secured by means of screws *h*³, or said plug may be secured to the bottom of the box, the only object of said plug, as hereinbefore stated, being to serve as a support and attachment for a chandelier or other hanger.

In practice the box is first placed in position on the board or boards *d*. The pipes *g* are then placed in position, as shown in Fig. 1, after which the concrete is filled in up to the tops of the I-beams *a*, and in this operation the box *e* is also filled with concrete, after which the flooring consisting of sleepers *c*³, ashes or other suitable material *c*², and the floor boards *c* is placed in position, and this completes the operation, of forming the floor and ceiling construction, it being understood that after the concrete has had time to set or become hard, the supporting or molding boards *d*—*d*² and *d*³ are removed, which operation leaves the bottom rim *e*³ of the box, the plug *h*², and the ends *g*² of the tubes *g* exposed, and a chandelier of any kind may be suspended from the plug *h*² and electric wires passed through the tubes *g* in the usual manner. It will also be understood that my improved outlet box may be used as a combination gas and electric fixture, if desired, all that is necessary being to pass a gas tube through the central opening *h* in the bottom of the box instead of the plug *h*² or said gas tube may be passed through said plug.

This improvement provides a perfectly safe, permanent and practical outlet box, and one which may be much more conveniently used in a floor and ceiling construction

than most other devices of this class, as now constructed, and my improved outlet box, used as described, avoids the necessity of cutting in to the concrete in order to place 5 the box, after the concrete work has been finished.

The bottom rim e^2 of the box is secured in position by means of screws i in the form of construction shown, but this may be done 10 in any desired manner, and in practice the body of the box, when not in use, may be provided with a detachable cover if desired, and changes in and modifications of the construction hereinbefore described may be 15 made, within the scope of the appended claim, without departing from the spirit of my invention or sacrificing its advantages.

Having fully described my invention what I claim as new and desire to secure by Letters Patent is:—

A ceiling outlet box open at the top and provided with a depending rim, the bottom of the box being also provided with pipe apertures or openings, and with a central opening to receive a hanger attaching device. 20 25

In testimony that I claim the foregoing as my invention I have signed my name in presence of the subscribing witnesses this 8th day of February 1912.

EDMUND M. REDDY.
